UNITED STATES PATENT OFFICE.

WILLIAM KINSEY, OF CINCINNATI, OHIO.

IMPROVEMENT IN THE PREPARATION OF COMPOUNDS FOR DRESSING LEATHER.

Specification forming part of Letters Patent No. **147,847**, dated February 24, 1874; application filed April 11, 1873.

To all whom it may concern:

Be it known that I, WILLIAM KINSEY, residing in Cincinnati, county of Hamilton, State of Ohio, have invented certain Improvements in the Preparation of Compounds used in Dressing Leather, of which the following is a specification:

My improvement relates to that class of compounds which are applied to leather as a dressing, for the purpose of rendering the same more supple, and increasing its durability. Such compounds are in common use, but none of those employed in this country, so far as my knowledge extends, have succeeded in imparting to leather that superior finish which characterizes the imported article known as "French leather."

The object of my improvement is to obtain a compound which, when applied as a dressing to leather, shall impart to it a finish nearly, if not quite, equal to that of the best French leather, and thus secure an article superior to any hitherto manufactured in this country. My improvements consist, first, in the substitution of an acid alone in place of the alkali and acid which are often used in the preparation of a leather-dressing; second, in the use of bees-wax, or any vegetable wax, as an additional ingredient in the preparation of leather-dressing, as hereinafter specified.

The compound embodying my improvement is prepared substantially as follows: Take about one gallon of any animal, fish, vegetable, or other oil, fat, or grease, except a drying-oil. Mix with it about one-quarter of a pound of bees-wax or any vegetable wax, previously melted, and treat the mixture with about two ounces of nitric acid, either pure or diluted. Next apply heat to the mixture until vapor begins to rise. The compound is then, after cooling, in a condition in which it may be offered for sale.

Just before being used, a variable propor-

tion of the mixture in common use known as "dubbin," consisting of tallow and fish-oil, should be added to it, after which it is ready for use according to the ordinary method of applying leather-dressings.

The proportions mentioned in the foregoing formula are not definite, but are given by way of illustration only. Furthermore, the bees-wax or other vegetable wax may be entirely omitted, in which case the compound will embody my first improvement only.

Some acid other than nitric might be employed, but the resulting preparation would be inferior to that containing nitric acid.

The application of heat greatly facilitates the preparation of the compound, but it may be omitted under favorable circumstances, as, for instance, when the weather is warm.

In those compounds which are in common use, bees-wax or other vegetable wax may be added to the oil, fat, or grease, and subsequently treated with an alkali or salt, in connection with them; and in this new use of bees-wax consists my second improvement aforesaid.

What I claim as my invention, and wish to secure by Letters Patent, is—

1. A leather-dressing consisting of animal, fish, vegetable, or other oil, fat, or grease, treated with nitric or other acid, either pure or diluted, with or without the application of heat, substantially as specified.

2. Bees-wax, or any vegetable wax, as a new and additional ingredient in the manufacture of leather-dressings, in which the oil, fat, or grease, together with the wax, are treated with an acid, as herein specified, or with an alkali or salt, such as are employed in preparations in common use.

WILLIAM KINSEY.
